UNITED STATES PATENT OFFICE.

HENRY REININGER, OF NEW ORLEANS, LOUISIANA.

COOLER.

SPECIFICATION forming part of Letters Patent No. 766,524, dated August 2, 1904.

Application filed September 26, 1903. Serial No. 174,743. (No model.)

To all whom it may concern:

Be it known that I, HENRY REININGER, a citizen of the United States, and a resident of New Orleans, in the parish of Orleans and State of Louisiana, have invented a new and Improved Cooler, of which the following is a full, clear, and exact description.

The invention relates to beer-coolers, such as shown and described in the Letters Patent of the United States, No. 626,934, granted to me June 13, 1899.

The object of the present invention is to provide a new and improved cooler for cooling wort, beer, and other liquids and arranged to increase the cooling efficiency of the cooling medium, to allow convenient and thorough cleaning of the various parts, to reduce the loss of the liquid to a minimum, and to prevent the liquid from coming in contact with the atmosphere during the cooling process.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement. Fig. 2 is an enlarged side elevation of the base portion of the improvement. Fig. 3 is a sectional plan view of the improvement on the line 3-3 of Fig. 2. Fig. 4 is an enlarged sectional side elevation of one of the set of circulating pipes and tubes. Fig. 5 is an inverted plan view of the lower head for the removable section. Fig. 6 is an inverted plan view of the upper head of the stationary section, parts being in section. Fig. 7 is an inverted plan view of the lower head of the stationary section, and Fig. 8 is a plan view of the upper head of the removable section.

The cooler consists, essentially, of a stationary section for the circulation of the brine or other cooling medium and of a removable section arranged for the circulation of the liquid to be cooled, the members of one section ex-

tending into the members of the other section, and the arrangement being such that the cooling medium and the liquid to be cooled flow in opposite directions to insure an effective cooling of the liquid. The stationary section is provided with superimposed heads A and B, fastened together by bolts, and the head B is bolted to a suitable base C. The heads A and B are provided with compartments A' and B', respectively, connected with each other, as indicated in Fig. 1, and from the top of each compartment B' in the head B extends a vertical central pipe D, around which are grouped a plurality of small pipes E, spaced from each other and from the central pipe, as plainly shown in Fig. 3. The pipes E are secured at their lower ends in a bonnet E', screwed or otherwise secured to the top of the head A and opening into a compartment A' thereof, and through each bonnet E' extends the corresponding central pipe D. The upper end of each central pipe D and the upper ends of the pipes E are secured in the bottom of a hood E² for connecting the said ends of the pipes E and D with each other to allow the cooling medium to pass from the upper ends of the pipes E by way of the hood E² into the central pipe D.

One of the compartments, A', is provided with an inlet A² for the brine or other cooling medium, (see Figs. 2 and 6,) so that the said cooling medium flows into this compartment and from the same by way of the pipes E in an upward direction to the hood E² and down the central pipe D into a compartment B' of the head B, and from this compartment the brine flows through a port B² in the top of the head B to the compartment A' adjacent to the inlet-compartment. (See Fig. 7.) The brine can now pass through the next set of pipes E and D to the next compartment B' and by the port B² to the following compartment until the brine has passed through all the sets of pipes D and E and hoods E² to finally reach the last compartment in the head B, from which the brine flows out by way of an outlet B². (See Figs. 2 and 7.)

The removable section above mentioned and

employed for the circulation of the liquid to be cooled is arranged as follows: The lower and upper heads F and G of the section are connected with each other by tubes H, each 5 sufficiently large for inclosing a set of pipes D and E and leaving room for the passage of the liquid to be cooled. The head F is adapted to be fastened by swing-bolts I to the top of the head A, as plainly shown in the drawings. The head F (see Fig. 5) is provided with 10 an inlet-compartment F', circulating-compartments F² and F³, and an outlet-compartment F⁴, of which the inlet-compartment F' and the outlet-compartment F⁴ are connected with 15 channels A³ and A⁴, formed in the side wall of the section A. (See Fig. 6.) The channels A³ and A⁴ are provided with an inlet A⁵ and an outlet A⁶ for the entrance and exit of the wort, beer, or other liquid to be cooled. The 20 head G is provided with compartments G', G², and G³, (see Fig. 8,) and the compartment F' is connected by a tube H with the compartment G', from which leads a second tube H to the compartment F² in the head F, and this 25 compartment is connected by a tube H with the compartment G², which in turn is connected by a tube H with the compartment F³. From this compartment leads a tube H to the compartment G³, connected by a tube H with 30 the exit-compartment F⁴, from which the liquid to be cooled passes to the channel A⁴ and to the outlet A⁶. It is expressly understood that each of the tubes H mentioned incloses a 35 set of pipes E and D, and the several tubes H are connected with each other by the corresponding compartments of the heads F and G, so that the liquid to be cooled circulates through the apparatus in a reverse direction to the travel of the cooling medium, as above 40 described. Furthermore, it will be seen that the liquid to be cooled in its passage through the pipes H completely surrounds all the pipes D and E to insure a quick and thorough cooling of the liquid by the cooling medium flowing 45 through the said sets of pipes E and D. The heads F and G are also connected with each other by a shell J for inclosing the tubes H, and this shell J is provided with an inlet J', adapted to be connected by a hose with 50 the outlet B³, so that the cooling medium for circulating through the sets of pipes, as described, can pass into the shell to surround the tubes H and to finally pass out through an outlet J² from the upper end of the shell. 55 It is understood, however, that the inlet J' may be connected with a separate cooling-medium supply; but when the cooling medium leaving the outlet B³ is of a sufficiently low temperature then this outlet B³ is preferably 60 connected with the inlet J'. On the shell J is also arranged a hand-hole J³ for cleaning the shell whenever it is desired to do so.

In order to allow of conveniently cleaning the section for the liquid to be cooled, the fol-

lowing arrangement is made: In the top of 65 the head A and at the center thereof is erected a support or standard K, preferably in the shape of a pipe, extending loosely through a central pipe L, connecting the heads F and G with each other. In the support or standard 70 K directly above the top of the head G are pivoted jaws N, pressed apart by a spring O, so as to extend with their outer free ends beyond the sides of the support or standard K. When the apparatus has been used for cool- 75 ing a liquid and it is desired to clean the parts through which the liquid to be cooled flows, then the swing-bolts I are swung loose and swung down to disconnect the head F from the head A, and then the operator takes hold 80 of handles F⁵ on the sides of the lower head F, and pushes the said head F, the head G, the pipes H, and the shell J, as well as the pipe L, upward a desired distance, and in doing so the jaws N partly close, and when 85 the operator releases the handles F⁵ then the jaws N press sufficiently hard against the inner surface of the pipe L to support the removable section on the standard K.

By the arrangement described convenient 90 access is had to the lower ends of the tubes H to permit of cleaning the same, and as the compartments F', F², F³, and F⁴ are now open they can also be readily cleansed from any 95 impurities that may adhere to the walls of the compartments. In a like manner the compartments G', G², and G³ in the head G can be cleansed by removing the top or cover thereof.

When the removable section has been 100 cleansed, the operator takes hold again of the handles F⁵ and draws the removable section downward until the base of the head F again rests on the top of the head A and then the 105 swing-bolts I are swung into position to fasten the head F again on the head A, it being understood, however, that care has to be taken that the compartments F' and F⁴ are moved in register with the channels A³ and A⁴ to establish a proper connection between the inlet 110 A⁵ and the outlet A⁶ with the inlet and outlet compartments F' and F⁴ of the head F of the removable section.

Having thus described my invention, I claim as new and desire to secure by Letters Patent— 115

1. A cooler having a removable section for the circulation of the liquid to be cooled, a stationary section for the circulation of the cooling medium, the sections extending one into the other, means for fastening the sections 120 together or disconnecting the same to allow of moving the sections apart, a support extending centrally from the stationary section, a tube on the removable section through which the support extends, and spring-pressed 125 jaws pivoted in the support and having their free ends normally extending beyond the sides of the support to engage the tube to support

the movable section when disconnected and moved apart from the stationary section, as set forth.

2. A cooler comprising a removable section for the circulation of the liquid to be cooled, a stationary section for the circulation of the cooling medium, the said removable section having heads provided with compartments, tubes connecting the heads with each other at alternate compartments, one of the heads having an inlet-compartment and a discharge-compartment, and the said stationary section having superimposed heads provided with connected compartments, central pipes extending from one head, bonnets secured to the other head and through which the said central pipes extend, a plurality of pipes grouped around each of the said central pipes, and secured to the said bonnets, the said central pipe and the pipes grouped around the same extending in a corresponding tube of the removable section, and a hood for each set of central pipes and the pipes grouped around the same, extending in a compartment in the head of the removable section remote from the stationary section, as set forth.

3. A cooler having a stationary section for the circulation of the cooling medium and provided with two superimposed heads each having a set of compartments, and sets of pipes, each set consisting of a central pipe leading from one of the compartments of the lower head, and a group of pipes surrounding the central pipe, a bonnet secured to the top of the other head at each compartment and opening into the same, the pipes of each group being secured at their lower ends in the corresponding bonnet, and a hood for each set of pipes and connecting the free ends of the pipes with each other, as set forth.

4. A cooler having a stationary section for the circulation of a cooling medium, a removable section for the circulation of the liquid to be cooled, the sections extending one in the other, a standard rising centrally from the stationary section and extending through a tube in the removable section, and spring-pressed jaws in the said standard, adapted to engage the tube in the removable section, as set forth.

5. A cooler having a stationary section for the circulation of a cooling medium, a removable section for the circulation of the liquid to be cooled, the sections extending one in the other, a standard rising centrally from the stationary section and extending through a tube in the removable section, spring-pressed jaws in the said standard, adapted to engage the tube in the removable section, and handles on the said removable section, for conveniently lifting or lowering the same, as set forth.

6. A cooler having a stationary section provided with sets of vertically-arranged pipes for the circulation of a cooling medium, each set consisting of a central pipe and a group of

pipes surrounding the central pipe, a removable section having a series of tubes for the circulation of the liquid to be cooled, the said tubes being each adapted to surround a set of pipes containing the cooling medium, a central vertical support on the stationary section, a centrally-arranged tube on the removable section through which the support extends, and spring-pressed jaws carried by the support directly above the top of the removable section and adapted to engage the central tube of the removable section.

7. A cooler having a removable section provided with a series of tubes for the circulation of the liquid to be cooled, a stationary section having sets of pipes for the circulation of the cooling medium, each set of pipes extending in the tubes of the removable section and consisting of a central pipe and a group of pipes surrounding the central pipe, the stationary section having an inlet and an outlet for the cooling medium and an inlet and an outlet for the liquid to be cooled, the stationary section being further provided with channels leading from the last-mentioned inlet and outlet and arranged to be connected with the inlet and outlet compartments of the removable section, and a shell for inclosing the removable section and having an inlet and an outlet of which the inlet is adapted to be connected with the outlet for the cooling medium of the stationary section, as set forth.

8. In a cooler a removable section for the circulation of the liquid to be cooled, and consisting of heads spaced apart and provided with compartments, tubes connecting the heads with each other at alternate compartments, one head having an inlet-compartment and an outlet-compartment for the entrance and exit of the liquid to be cooled, and a stationary section to which the said head is adapted to be fastened, the stationary section being provided with channels in its side walls, connected with the said inlet and outlet compartments of the head, the channels being provided respectively with an inlet and an outlet, as set forth.

9. In a cooler a stationary section for the circulation of the cooling medium and comprising a base, two superimposed heads fastened together and secured to said base, the heads being provided with compartments, a vertical central pipe extending from the top of each compartment in the lower head, bonnets secured to the top of the upper one of said heads and opening into the compartments of said upper head, a series of pipes grouped around each of said central pipes and secured at their lower ends in the corresponding bonnet, the said central pipes extending through the respective bonnets, a hood to the bottom of which the upper end of each central pipe and the upper ends of the series of pipes are secured to permit the cooling medium to pass

from the group of pipes by way of the hood into the central pipe, an inlet for the cooling medium leading to one of the compartments of the upper head, and an outlet leading from 5 one of the compartments in the lower head, the top of the lower head being provided with ports connecting compartments in the upper and lower head, the several compartments, pipes, hoods and ports forming a continuous 10 passage for the cooling medium, leading from the said inlet in the upper head to the outlet in the lower head, as set forth.

10. The combination in a cooler, of a movable section comprising two spaced heads connected together by means of vertical tubes, 15 an outer jacket surrounding said tubes and connected with the heads, a cover for the top head, a stationary section having superimposed heads, the upper head being adapted 20 to be engaged by the open end of the lower head of the movable section, and swing-bolts carried by the upper head of the stationary section and engaging the lower head of the movable section to securely fasten the said 25 heads together to form closed compartments in the lower head of the movable section, the stationary section having sets of vertically-arranged pipes, each set extending in a tube of the movable section and comprising a central pipe and a group of pipes surrounding 30 the central pipe, as described.

11. The combination of the two sections one adapted for the circulation of the liquid to be cooled, the other for the cooling medium, the section for the cooling medium comprising heads having connected compartments, and a plurality of sets of pipes connected with the compartments, each set comprising a central pipe and a group of pipes 40 surrounding the central pipe, and the section for the liquid to be cooled being arranged to slip over the other section and comprising a series of tubes each adapted when in position to surround one of the sets of pipes containing 45 the cooling medium, the section for the liquid to be cooled being also provided with compartments forming with the tubes a continuous passage for the said liquid through the several compartments and tubes, one of 50 the heads of the section for the cooling medium having an inlet and an outlet for the liquid to be cooled, the said inlet being connected with one of said compartments and the outlet with another of said compartments, the 55 liquid to be cooled passing in an opposite direction to the cooling medium for the purpose described.

12. In a cooler, the combination of a section for the circulation of a cooling medium 60 and provided with two superimposed heads each having a set of compartments, sets of pipes, each set consisting of a central pipe leading from one of the compartments of the lower head and a group of pipes surrounding

the central pipe, a bonnet secured to the top 65 of the other head at each compartment and opening into the same, the pipes of each group being secured at their lower ends in the corresponding bonnet, and a hood for each set of pipes and connecting the free ends 70 of the pipes with each other, and a section for the circulation of the liquid to be cooled and including tubes containing the liquid to be cooled, the said tubes surrounding the sets of pipes and the liquid in said tubes being distributed around the pipes in a comparatively thin film, and an outer jacket connected with the section containing the liquid to be cooled, the jacket surrounding the tubes and pipes and into which the cooling medium is led, after 75 it has done its work in the series of pipes, to act on the outer surface of the tubes containing the liquid to be cooled, for the purpose described.

13. The combination of a stationary section 80 for the circulation of a cooling medium, a removable section for circulation of a liquid to be cooled, a vertical tube extending centrally through the movable section, a pipe securely fastened to the stationary section and extending 85 through and beyond the upper end of said center tube of the movable section, and an automatic catch carried by the said pipe above the top of the removable section and adapted 90 to engage the inner surface of said center tube, 95 when the movable section is raised for the purpose described.

14. The combination of a stationary section for the circulation of a cooling medium, a section for the circulation of a liquid to be cooled, 10 the latter section having heads connected by a central vertical pipe and adapted to be raised off the stationary section, a standard secured to the stationary section and extending vertically through said pipe and projecting above the upper head of the movable section, the said standard forming a guide for the movable section, on which the movable section has vertical and rotary movement, an automatic catch secured to said standard and adapted to engage the inner surface of said central pipe to hold said movable section in raised position, and handles on the movable section, as set forth.

15. A cooler comprising a movable section 11 for the circulation of the liquid to be cooled consisting of heads spaced apart and provided with compartments, tubes connecting the heads with each other at alternate compartments, one head having an inlet-compartment and an outlet-compartment for the entrance 12 and exit of the liquid to be cooled, a stationary section for the cooling medium comprising two heads provided with connected compartments, central pipes extending from one head, a plurality of pipes grouped around each of the 12 said central pipes and extending from the other head, the central pipe and the pipes grouped around it being arranged to extend in a corre-

sponding tube of the movable section, and a hood for each central pipe and the pipes grouped around the same and extending in a compartment in the head of the movable section, the heads of the stationary section being provided respectively with an inlet and an outlet for the cooling medium, and one of said heads having channels in its side walls connected with the said inlet and outlet compartments of the head of the movable section, the

channels being provided respectively with an inlet and an outlet for the liquid to be cooled, as set forth.

In testimony whereof I have signed my name to this specification in the presence of two subscribing witnesses. 15
